DESIGN FOR A TABLE FOR RAY TREATMENTS

Warren F. Clark, Warren, Pa.

Application December 8, 1937, Serial No. 73,466

Term of patent 3½ years

To all whom it may concern:

Be it known that I, Warren F. Clark, a citizen of the United States, residing at Warren, in the county of Warren and State of Pennsylvania, have invented a new, original, and ornamental Design for a Table for Ray Treatments, of which the following is a specification, reference being had to the accompanying drawing, forming a part thereof, in which:

Fig. 1 is a perspective view of a table for ray treatments showing my new design, and

Fig. 2 is an end elevation of the same.

The design as herein illustrated is embodied in an elongated table top with a hood positioned above a portion thereof, all carried upon a supporting structure which is substantially closed at the ends of the table.

I claim:

The ornamental design for a table for ray treatments, substantially as herein shown and described.

WARREN F. CLARK.
